UNITED STATES PATENT OFFICE.

SADIE F. BAILEY, OF NORTH WARREN, PENNSYLVANIA.

SANITARY COMMODE-PROTECTOR.

1,209,656.

Specification of Letters Patent. Patented Dec. 26, 1916.

Application filed August 25, 1914. Serial No. 858,458.

To all whom it may concern:

Be it known that I, SADIE F. BAILEY, a citizen of the United States, residing at North Warren, in the county of Warren, State of Pennsylvania, have invented certain new and useful Improvements in Sanitary Commode-Protectors; and I do hereby declare the following to be a full, clear, and exact description of the invention, such as will enable others skilled in the art to which it appertains to make and use the same.

This invention relates to improvements in sanitary seat protectors.

The principal object of the invention is to provide a simple and comparatively cheap device of this character which will readily fit the seat and which will be of a material comfortable to the user.

Another object is to provide a device which is adapted to be placed on a commode seat and which will prevent the spread of disease.

Other objects and advantages will be apparent from the following description, when taken in connection with the accompanying drawings.

In the drawings: Figure 1 is a plan view of a commode seat showing my invention in position thereon. Fig. 2 is a transverse sectional view on the line 2-2 of Fig. 1, slightly enlarged.

Referring particularly to the accompanying drawings, 10 represents a commode seat which is provided with the usual central opening 11, the side walls 12 of which incline downwardly and inwardly toward the opening. The upper face of the seat is flat and horizontal as indicated at 13. The protective covering is formed preferably of sheet rubber and is in the form of a flat ring 14 in which is formed an opening 15 of a size and shape like that of the seat.

The marginal edge of the opening 15 is arranged to lie over the marginal edge of the opening 11, the body portion of the ring 14 lying against the inclined wall 12. The outer marginal edge of the ring is thickened as indicated at 16 and rests on the flat face 13 of the seat. This thickened edge stiffens the ring and holds the same against wrinkling as well as preventing the ring from doubling up and slipping through the ring 11 of the seat. In each end of the protector is a hanger 17 whereby the device may be suspended when not in use.

I do not limit my invention to the exact details of construction, combination and arrangement of parts, as herewith illustrated and described, but my invention may only be limited by a reasonable interpretation of the claims.

What is claimed is:

1. As an article of manufacture, a protective covering for a commode seat comprising a ring formed of rubber and adapted to seat on the horizontal outer peripheral portion of the top of a commode seat and a downwardly inclined web formed integrally therewith at its inner periphery and of lesser thickness than the ring and provided with an opening coincident with the inner periphery of the seat.

2. A commode protector comprising an integral rubber ring having a relatively flexible inner portion and a relatively stiff outer portion.

In testimony whereof I affix my signature, in the presence of two witnesses.

SADIE F. BAILEY.
